UNITED STATES PATENT OFFICE.

THOMAS I. RANKIN, OF PHILADELPHIA, PENNSYLVANIA, ASSIGNOR TO THE
ABRAM COX STOVE COMPANY, OF SAME PLACE.

DESIGN FOR A COOKING-STOVE.

SPECIFICATION forming part of Design No. 34,910, dated August 6, 1901.

Application filed September 8, 1900. Serial No. 29,465. Term of patent 7 years.

To all whom it may concern:

Be it known that I, THOMAS I. RANKIN, a citizen of the United States, residing in Philadelphia, Pennsylvania, have invented and produced a new and original Design for a Cooking-Stove, of which the following is a specification.

My design for a cooking-stove is illustrated in the accompanying drawing, in which the figure represents the stove in perspective.

A is the body of the stove, having a top plate *a*, an oven-door *B*, a fire-door *C*, an ash-pit door *D*, and hot-water reservoir *E*.

F is the base-section of the stove, having a 15 legs *f*, and *G* is the mantle-support, having a mantle *g*.

The ornamentation of the stove is made up principally of scrolled figures. The design of the base of the stove consists of a scroll-shield *f'* at each corner and a scrolled medallion *f''* at the center, united to the shields at the corners by a series of foliated scrolls. On each foot *f* below the medallion *f''* are scrolls *f'''*.

25 The oven-door *B* has a central name-plate bordered by a plain scroll *b* and at the bottom with a shell-scroll *b'*, and at each side with an inverted shell-scroll *b''*. At the upper left-hand corner of the door is a fluted

scroll *b'''*, and the balance of the ornamentation is made up of shield, shell, and foliated scrolls, as shown.

The fire and ash-pit doors *C* and *D* are ornamented in keeping with the oven-door, and the face of the hot-water reservoir is 35 ornamented in keeping with the oven-door, having a shell-scroll *e* at one lower corner, a fan-scroll *e'* at the opposite lower corner, and above the fan-scroll an ornamental cross-bar medallion *e''*.

40 The mantle-support *G* is in the form of a large shield, having a central ornamental panel circular in form and having star-shaped figures surrounding a rosette at the center. Bordering the shield are large ornamental scrolls *G'*, which are in keeping with the general design of the stove.

I claim—

20 The design for a stove as herein described and as illustrated in the accompanying drawing.

In testimony whereof I have signed my name to this specification in the presence of two subscribing witnesses.

THOMAS I. RANKIN.
